UNITED STATES PATENT OFFICE.

CHARLES J. STROKE, OF BUFFALO, NEW YORK.

BURGLAR-ALARM AND LOCK.

1,299,808.

Specification of Letters Patent.

Patented Apr. 8, 1919.

Original application filed June 30, 1916, Serial No. 106,916. Divided and this application filed October 20, 1916. Serial No. 126,683.

To all whom it may concern:

Be it known that I, CHARLES J. STROKE, a citizen of the United States, residing at Buffalo, in the county of Erie and State of New York, have invented certain new and useful Improvements in Burglar-Alarms and Locks; and I do hereby declare the following to be a full, clear, and exact description of the invention, such as will enable others skilled in the art to which it appertains to make and use the same.

This invention relates to a burglar alarm and lock, being a division of my application filed June 30, 1916, and serially numbered 106,916, and has for its primary object the provision of means permanently attached to a door jamb or to the upper sash of a window, which is capable of being swung into the path of the door or lower sash to prevent the door or lower sash from being opened.

Another object of this invention is to provide a supporting plate pivotally secured to the door jamb or upper sash of the window and having a bell adjustably secured thereto which is adapted to be swung into the path of the door or lower sash of a window whereby upon an unauthorized person endeavoring to open either the door or lower sash it will engage the bell and sound an alarm and further prevent movement of the door or lower sash into open position.

A further object of this invention is the provision of a burglar alarm and lock of the above stated character which will be simple, durable and efficient and which may be manufactured and sold at a comparatively small cost.

With these and other objects in view as will become more apparent as the description proceeds, the invention consists in certain novel features of construction, combination and arrangement of parts as will be hereinafter more fully described and claimed.

For a complete understanding of my invention, reference will be had to the following description and accompanying drawings, in which:

Figure 1 is a front elevation of a burglar alarm and lock, constructed in accordance with my invention, illustrating it applied to a door jamb,

Fig. 2 is a top plan view of the same,

Fig. 3 is a top plan view partly in section illustrating it applied to a window sash.

Referring in detail to the drawing, the numeral 1 indicates a door and 2 the jamb to which my invention may be applied. The numerals 3 and 4 indicate upper and lower window sashes respectively of a window frame, to which my invention may be applied.

An elongated supporting plate 5 is provided with an elongated slot 6 adjacent one end. The opposite end of the plate is bent at right angles as illustrated at 7 and is apertured to receive a bolt 8. The bolt 8 is carried by one arm portion of an L-shaped attaching plate 9 which has its other arm portion provided with a plurality of openings to receive screws 10 or other like fastening elements.

A plate 11 is positioned upon the supporting plate 5 and is adjustably secured thereto by a bolt 12 extending through the elongated slot 6 and receiving a wing nut 13, whereby loosening the tension of the wing nut 13 upon the bolt 12, the base plate 11 may be adjusted along the supporting plate 5. A bell 14 of the spring type having a control button 15 thereon is secured to the base plate 11. The base plate 11 has one of its ends bent at right angles as illustrated at 16 and is bifurcated to receive the button 15 of the bell 14.

In operation, when it is desired to attach my invention to a door jamb, the L-shaped attaching plate 9 is secured to the jamb 2 by the screws 10 as clearly illustrated in Fig. 2, whereby the device is permanently secured to the door jamb. When desiring to render the device operable, the supporting plate 5 is swung upon the bolt 8 until its right angled end 7 overlies the free arm portion of the L-shaped attaching plate 9, thus positioning the bell 14 within the path of the door 1. If the door 1 is moved in the direction of an open position it will engage the button 15 and cause the bell 14 to sound an alarm. The door is further prevented from moving in an open position by the right angled bifurcated end 16 of the base plate 11 and the door will engage the same and pushing the button 15 will sound the bell, thus preventing the door from being opened by an unauthorized person.

In applying this invention to window

sashes the L-shaped attaching plate 9 is secured to the upper sash by the screws 10 and by swinging the supporting plate 5 so that the right angled end 7 overlies the free arm portion of the L-shaped plate 9, the bell will be positioned in the path of the lower sash. Upon upward movement of the lower sash it will engage the button 15 causing the bell 14 to give an alarm, the lower sash also being prevented from further upward movement by the right angled end 16 of the supporting plate 11.

From the foregoing description taken in connection with the accompanying drawings, 15 it will be readily noted that a device has been provided which may be quickly applied to either a window or door to prevent the same from being opened and if endeavored to be opened by an unauthorized person an alarm will be sounded by the bell.

While I have shown and described the preferred embodiment of my invention, it will be understood that minor changes in the construction, combination and arrange-

ment of parts may be made without departing from the spirit and scope of the invention as claimed. 25

Having thus fully described my invention, I claim:

A device of the character described comprising, an L-shaped plate adapted for attachment to the jamb of a door; an elongated supporting plate having one end portion bent at right angles and contacting with one arm of said L-shaped plate; a pivot element extending vertically through the angularly disposed portion of the supporting plate and the contacting arm of the L-shaped plate; and a stop plate adjustably secured to said supporting plate, said stop plate having its inner end portion angularly disposed for contact with the door. 30 35 40

In testimony whereof I affix my signature in presence of two witnesses.

CHARLES J. STROKE.

Witnesses:

W.M. P. STROKE,
HOWARD G. BEHLING.
